FIREPLACE SCREEN

Joseph H. Babros and Joseph Komada,
Los Angeles, Calif.

Application February 20, 1950, Serial No. 145,216

2 Claims. (Cl. 160—126)

1

This invention relates to improvements in screens adapted to be positioned in front of open fireplaces for the purpose of confining sparks therein.

An object of the invention is to provide an improved fireplace screen consisting essentially of a rectangular frame adapted to be supported in upright position before a fireplace and which has metallic curtains slidably suspended therein that can be simultaneously opened or closed by means of a chain that is trained over a pulley mounted on the underside of the top of the frame. This chain has its free ends extending through one side of the frame so as to be accessible at the side thereof and on pulling one of the free ends of the chain both curtains may be simultaneously shifted to open or closed position depending upon which end of the chain is pulled.

More specifically an object of the invention is to provide a novel, simple and inexpensive means for rotatably supporting the pulley on the underside of the top of the frame and over which the chain is trained.

Another object of the invention is to provide a simple and inexpensive means for supporting the reaches of the chain on the underside of the top adjacent the center of the top so that these reaches that extend from the pulley to the side of the frame through which the chain extends will not hang down from the top in an objectionable manner.

A further object of the invention is to provide a simple and easily manufactured construction for supporting the inner ends of the rods that slidably support the curtains on the underside of the top of the frame so that these inner ends of the rods will be adequately supported in mutually overlapping relation.

Other objects of the invention are to provide a simple mechanism for training the chain as it leads through the side of the frame and to provide a simple and inexpensive construction for connecting the sides and top of the frame to each other.

With the foregoing and other objects in view, which will be made manifest in the following detailed description and specifically pointed out in the appended claims, reference is had to the accompanying drawings for an illustrative embodiment of the invention, wherein:

Figure 1 is a view in front elevation of the fireplace screen embodying the present invention.

Fig. 2 is a partial view in rear elevation of the upper portion of the fireplace screen showing the internal construction of the top thereof. This

2

view is taken from the reverse side of the screen as viewed in Fig. 1.

Fig. 3 is a partial view illustrating details of construction of how the top and sides of the frame are connected to each other.

Fig. 4 is a vertical section taken substantially upon the line 4—4 upon Fig. 2 in the direction indicated.

Fig. 5 is a vertical section taken substantially upon the line 5—5 upon Fig. 2 in the direction indicated.

Fig. 6 is a vertical section taken substantially upon the line 6—6 upon Fig. 2 in the direction indicated.

Fig. 7 is a vertical section taken substantially upon the line 7—7 upon Fig. 2 in the direction indicated.

Referring to the accompanying drawings wherein similar reference characters designate similar parts throughout, the improved fireplace screen consists of a rectangular metal frame having a bottom 10, sides 11 and 12, and a top 13. Legs 14 and 15 are secured to the forward sides of the sides 11 and 12 and serve to support the frame in an upright position. Suitable feet (not shown) may be secured to the rear side of the bottom 10 so as to extend rearwardly therefrom and prevent the frame from being tilted rearwardly.

The sides 11 and 12 and the top 13 are preferably formed of angle iron or brass which is angular in cross section similar to angle iron. One feature of the invention concerns the manner in which the top 13 is connected to the sides 11 and 12. As illustrated in Fig. 3, the upper end of the forward face of each of the sides is beveled off as indicated at 16, and adjacent this bevel the metal is bent rearwardly as indicated at 17 as shown in Fig. 7, thus forming a slight inclined shoulder adjacent the top of each of the sides 11 and 12. The top 13 has its forward face beveled off complementary to such inclined shoulder except for a downwardly extending finger 18 which is receivable in a slot or opening 19 formed in the shoulder 17. The top face of the angle iron that forms the top 13 is extended and bent downwardly as indicated at 20 so as to overlie the outer side faces of the sides 11 and 12. These portions 20 have apertures therein indicated at 21 that are alignable with apertures 22 in the upper ends of the outer faces of the sides 11 and 12 designed to receive the threaded ends 23 of shouldered supporting rods 24 and 25. The shoulders on these supporting rods are indicated at 26 and acorn nuts or the equivalent, indicated at 27, are ap-

plicable to the shanks 23 where they extend through the apertures 22 and 21. It will thus be appreciated that, with the top 13 and the sides 11 and 12 formed in the manner illustrated, the top can be assembled with the sides 11 and 12 very readily by merely forcing the finger 18 at each end of the top down through the aperture 19 until the beveled edge at each end of the top 13 engages the shoulder formed at 17. In this position the apertures 22 and 21 will align and on an insertion of the shanks 23 on the rods 24 and 25 and the application of the acorn nuts 27, the parts of the frame are effectively locked together. These parts, however, can be readily disassembled from each other for purposes of storage and shipment.

The joint between the top and the sides is normally concealed on the forward side of the frame by the application of an ornamental emblem 28. This emblem may have a stud integral therewith that extends through the joint and which is threaded for the application of a nut 29. In lieu thereof a bolt may be employed to bolt the emblem in position to overlie the joint.

The rods 24 and 25 have their inner ends in mutually overlapping relation within the top 13 and serve to slidably support or suspend sections or curtains 30 and 31 from the top. These curtains are slidably suspended from their respective rods by means of rings 32, and a chain 33 which is trained over a rotatable pulley 34 has its reaches secured to one ring of each curtain as indicated at 35 and 36, respectively. The ends of the chain extend through the side 11 and hang downwardly adjacent the outer side thereof. Thus, by pulling on one end of the chain the curtains may be simultaneously caused to slide on their respective rods 24 and 25 into open or closed position depending upon which end of the chain 33 is pulled. The connections 35 and 36 are usually made to rings 32 that are somewhat spaced from the inner edges of their respective curtains and wires 37 extend from such rings through rings at the edges and downwardly through the mesh of the metallic curtains. Consequently the inner edges of the curtains will be moved in advance of the connections 35 and 36 so that on closing the curtains across the frame the inner edges of the curtains will be capable of assuming mutually overlapping positions and thus effectively serve to confine any sparks from the fireplace.

One feature of the invention relates to the manner in which the pulley 34 is rotatably mounted on the underside of the top face of the top 13. This is accomplished by providing a small plate 40 and securing thereto such as by soldering or brazing a U-shaped bracket 41 the center of which is spaced from the plate a distance equal to the thickness of the pulley 34. A hole 42 is formed in the plate 40 by piercing the metal downwardly as shown in Fig. 4 and in a similar manner a hole 43 is formed in the bracket 41 by piercing the metal upwardly. The metal thus pierced enters the hole in the center of the pulley 34 and forms an adequate bearing to rotatably support the pulley. The plate and bracket 40 and 41, after having been thus assembled together with the pulley 34, can be secured to the underside of the top 13 such as by soldering or brazing. This form of construction provides a very simple and inexpensive means for rotatably mounting the pulley 34 on the underside of the top.

It is desirable to support the reaches of the

chain between the pulley 34 and the side 11 so that these reaches will not objectionably hang down below the bottom edge of the forward face of the top 13. Provision must also be made for supporting the inner ends of the rods 24 and 25. To this end channel-shaped stampings are provided, indicated at 44 and 45. These stampings have angular brackets 46 and 47 secured to their sides. The lower ends of these brackets are formed so as to provide a reverse curl, the curls being indicated at 48 and 49. These curls are designed to slidably receive the inner ends of the rods 24 and 25 respectively. The channels 44 and 45 have the brackets 46 and 47 assembled therewith prior to installation on the underside of the top and when the brackets have been assembled the channels may be secured to the underside of the top 13 such as by soldering or brazing. The channels 44 and 45 are located near but not exactly on the center of the top 13 so that their brackets 46 and 47 will properly be positioned to engage and support the rods 24 and 25 which, as above stated, are in mutually overlapping relation to each other. As the channels 44 and 45 can be readily stamped out, this construction forms a simple and easily applied device for not only supporting the inner ends of the rods but slidably supporting the reaches of the chain between the pulley 34 and the side 11 so that these reaches will not objectionably hang down below the top 13.

Near the side 11 an additional stamping, indicated at 50, is provided, this stamping provided two channels 51 and 52 for the chain reaches as they approach the side 11. The ends of the channels are bent downwardly as indicated at 53 so as to lead to two apertures that are formed at the junction between the top 13 and the side 11. The reaches of the chain are thus trained across the smooth downwardly bent ends of the channels 51 and 52 so that when an end of the chain is pulled it may move with very little friction through the channels provided by the stamping 50 and the channels 44 and 45.

From the above described construction it will be appreciated that the parts of the improved fire screen can be very easily and economically manufactured and assembled. Although the plate 40, the bracket 41, and pulley 34, the channels 44 and 45 and their brackets 46 and 47, and the stamping 50 are permanently assembled with the top 13, the top can be easily and quickly disassembled from the sides 11 and 12 by merely removing the acorn nuts 27 and sliding the rods 24 and 25 inwardly until their shanks 23 are withdrawn from the aligned apertures. In so doing the curtains 30 and 31 can be removed at any time desired for cleaning purposes and, if desired, the entire frame can be knocked down for storage or shipping purposes. When the screen is in use the curtains 30 and 31 can be simultaneously open or closed by merely pulling on one end of the chain and when the curtains are in fully closed position their inner edges are disposed in overlapping relation to effectively confine sparks.

Various changes may be made in the details of the construction without departing from the spirit and scope of the invention as defined by the appended claims.

We claim:

1. A fireplace screen comprising a frame having sides and a connecting top, one of said sides

having apertures therein, channels secured to the under side of the top adjacent the center thereof in spaced parallel relationship to each other, rod supports secured to the channels and extending downwardly therebeneath, rods secured to the sides and extending towards each other beneath the top and having their inner ends disposed in overlapping relationship and supported by their respective rod supports, parallel channels secured to the under side of the top adjacent one end thereof leading toward the apertures in said one side, a pulley mounted for rotation on the under side of the top adjacent that end which is remote from the last-mentioned channels, a chain trained over the pulley and having reaches extending through the channels and through the mentioned apertures, and curtains slidably mounted on the rods and connected to the reaches respectively so as to be capable of being simultaneously opened or closed thereby.

2. A fireplace screen comprising a frame having sides and a connecting top, one of said sides having apertures therein, channels secured to the under side of the top adjacent the center thereof in spaced parallel relationship to each other, rod supports connected to the top and extending downwardly therefrom to points below the channels, rods secured to the sides and extending towards each other beneath the top and having their inner ends disposed in overlapping relationship and supported by their re-

spective rod supports, parallel channels secured to the under side of the top adjacent one end thereof leading toward the apertures in said one side, a pulley mounted for rotation on the under side of the top adjacent that end which is remote from the last-mentioned channels, a chain trained over the pulley having reaches extending through the channels and through the mentioned apertures, and curtains slidably mounted on the rods and connected to the reaches respectively so as to be simultaneously opened or closed thereby.
